CLAIM

The ornamental design for an architectural fixture, as shown and described.

DESCRIPTION

FIG. 1 is a perspective view of our new design for an architectural fixture;

FIG. 2 is a front elevational view thereof;

FIG. 3 is a right elevational view thereof;

FIG. 4 is a rear elevational view thereof;

FIG. 5 is a left elevational view thereof;

FIG. 6 is a bottom plan view thereof; and,

FIG. 7 is a top plan view thereof.

The portions of the article shown in evenly dashed lines in the accompanying figures illustrate environment that form no part of the claimed design. The dash-dot-dash lines illustrate boundaries and form no part thereof.
